UNITED STATES PATENT OFFICE.

SIDNEY GEORGE BROWN, OF NORTH ACTON, ENGLAND.

MEANS FOR THE PRODUCTION OR REPRODUCTION OF SOUND OR LIKE VIBRATIONS.

Application filed September 4, 1923, Serial No. 660,748, and in Great Britain October 12, 1922.

This invention relates to improved means by which sound or mechanical vibrations may be produced or reproduced by the method in which a member rubbing upon a 5 relatively moving surface is set into vibration by the alternate gripping and release of the contacting surfaces. I have found that if one of the surfaces is of polished or glass-like nature it is possible to reproduce sounds such as speech 10 sounds with great clearness and considerable intensity by controlling in a vibratory manner the rubbing member, and according to one feature of this invention I employ with 15 a surface of this type a rubbing member which lies closely upon the surface over a substantial area and is maintained by pressure against the surface, the pressure varying by vibratory action under the control 20 of the source of primary vibrations, the said rubbing member being connected to a sound emitting or transmitting member so as to set up secondary vibrations, by the alternate pull and release of the rubbing 25 member, which are of amplitude and period depending upon the amplitude and period of the controlling vibrations. The rubbing surface is carefully fitted to lie on the relatively moving surface and is preferably 30 ground to shape. The moving surface, which may be of polished glass or hard metal such as steel, is usually in the form of a rotating disc driven at a moderate speed by clockwork or other mechanism, or a rotating drum similarly driven or a cone, and 35 the polished surface may be coated with a very thin film of a slightly "tacky" material which is so thin that it does not give substantial adhesion, but makes the clinging 40 action of the rubbing member more controllable and regular in its action. The film should be so thin as to produce hardly any visible effect. In the case of a rotating drum the rubbing member may consist of a flexible 45 steel-backed cork strip lapping round a portion of the circumference and pressed towards its free end by the controlling source of vibrations.

The controlling primary vibrations may 50 be derived from a telephone receiver, a voice operated diaphragm, a gramophone needle or other vibratory member and the transmission to the rubbing member is preferably effected by a small pin or stud, which 55 may be flexible and may be arranged to have

a variable slope by mounting the source of vibrations adjustably about an axis passing through the point of contact of the pin and rubbing member.

The main pressure of the rubbing member 60 may be determined by the mounting of the telephone receiver or other source of primary vibrations, which is arranged upon a rocking support provided with a balancing weight by which the pressure on the rubbing member may be regulated; or the telephone may be separately mounted on a rocking support and the diaphragm for producing the secondary vibrations mounted on a rigid or independently displaceable support 70 carrying a sound horn.

In order that the said invention may be clearly understood and readily carried into effect, the same will now be described more fully with reference to the accompanying 75 drawings, in which:—

Figure 1 is a plan and Figure 2 a side elevation of one form of apparatus embodying this invention.

Figure 3 is a detail view showing a portion of the apparatus partly in plan and partly in section.

Figure 4 is a detail view of a rubbing member in the form of a flat pad as used in the apparatus of Figures 1, 2 and 3.

Figures 5 and 6 are, respectively, a plan and elevation of a modified construction of apparatus of similar general type to that shown in Figures 1, 2 and 3.

Figures 7 and 8 are a plan and an elevation showing a further modification of which Figure 9 is a detail view.

Figure 10 illustrates a modification employing a rotating drum or cylinder.

Referring to the construction shown in 95 Figures 1 to 4, A is the supporting plate or base of the instrument, which may form the top of a box containing clockwork mechanism of the type employed in gramophones. B is the rotating disc which is driven at a 100 steady moderate rate, considerably slower than the usual gramophone disc drive, the disc B having a very smooth or polished upper surface. It is mounted upon the rotating carrier b driven through the vertical spindle b¹. C is the rubbing member in the form of a small flat disc, the rubbing surface of which is formed by the thin face disc c, which may be of cork, this material having 105 been found to give good results, the face 110

disc being cemented on the thin steel plate or disc c^1 . D is the flexible connection from the disc C to the sound emitting or transmitting member shown in the form of a conical diaphragm E, the flexible connection comprising a doubled filament or thread firmly secured on the back of the disc C and attached at one end to the diaphragm E through the hook e and at the other end attached to the spring d carried by the adjustable stationary member d^1 . The connection D and disc C can therefore be immediately detached and fitted in place as required. The direct connection to a diaphragm is not necessary and connection may be made through a lever as in a gramophone sound box.

F is a telephone receiver which may, however, be replaced by any other source of controlling oscillations. This receiver is mounted over the disc B towards one side so that its centre is over the centre of the rubbing disc C, a pin f attached to the vibrating member of the receiver, such as a diaphragm or reed, resting upon the back of the disc C. The receiver is mounted on the rocking frame G supported by the pivot pins g carried in the standards a of the base A, the frame being provided with the adjustable balancing weight g^1 on the arm g^2 so that the pressure exerted by the pin f on the back of the disc C is adjusted to the required amount.

H is a sound horn of ordinary gramophone type, the smaller end of the horn extending to the back of the face plate g^3 of the frame G, this plate having a central opening in which the conical diaphragm E is secured around its edge by means of a connecting member g^4 which extends into the smaller end of the horn H. As the axis of adjustment of the frame G passes through the smaller end of the horn close to its extremity the frame can be raised or turned back to raise the receiver from the rotating disc without interfering with the horn, the inner end of the connecting member g^4 forming a box which maintains the inner end of the horn closed, but provides a sound aperture leading into the horn from the space at the back of the diaphragm E.

As already described, the rotating disc B may have a very fine film of friction producing material, such as resin, as this has been found to give a better result than the untreated polished surface and enables the gripping surface to be renewed at any time so that a constant condition can be ensured. The pin f which bears on the back of the pad or disc C is preferably of resilient material to allow of the slight lateral vibratory movements without putting undue stresses on the controlling receiver or equivalent controlling instrument.

65 The modified construction of Figures 5

and 6 provides for the adjustment of the angle of the pin f. The telephone receiver F or equivalent controlling instrument is mounted in a carrier J, shown in the form of an encircling ring or strap, which carrier is provided with a downwardly extending lug j pivotally attached to the end g^5 of an arm g^6 forming part of the frame G and extending from the cover g^7 of the diaphragm E. The pivotal axis of the carrier J passes through the end of the pin f so that by adjusting the carrier around the axis the pin f can be given any desired backward or forward slope. If the slope is in the direction of motion of the disc B the tendency of the pin is to yield to the pull on the pad C due to the rotation, while if the slope is in the opposite direction the tendency is to increase the grip. The amplification may therefore be carried by adjustment of the angle. The lug j of the carrier is secured in adjusted position by the set screw j^1 .

In the construction of Figures 5 and 6 the horn H serves as part of the pivotal support of the frame G, the box member g^8 behind the diaphragm being of elbow form and projecting into the end of the horn, which is provided with a small cross bearing piece h receiving a pivot pin g^9 fixed at the end of the elbow piece g^8 . The pivot g^9 is in line with the opposite pivot pin g. The balance weight g^1 is shown mounted on two arms pivoted at g^{10} above the axis of the elbow piece g^8 so that when the frame G is turned up to lift the receiver clear of the rotating disc the weight will hold it up out of the way.

In the modification shown in Figures 7, 8 and 9 the mounting of the receiver F is independent of the horn mounting, the horn H being carried by the elbow g^{11} mounted on a fixed support formed by a wall of the enclosing box G^1 which carries the diaphragm inside the cover g^{12} . The receiver F is mounted in the ring carrier J^1 carried by the support j^2 pivoted at j^3 in the fixed bracket a mounted on the base A which forms the top of the box A^1 . The carrier J^1 is itself pivoted at j^4 in the support j^2 with a limited movement allowing it to be turned back with the receiver F when the instrument is to be thrown out of action. The counterbalancing weight j^5 on an arm j^6 of the pivoted support j^2 determines the pressure exerted by the pin f of the receiver F on the back of the pad C. The receiver may be arranged for angular adjustment of the pin f as in the previously described arrangement.

Figure 8 shows a simple means for stopping the motor driven disc B, in the form of a spring brake arm K adapted to bear on the edge of the supporting disc b, the arm being carried on the underside of the base A and passing through an aperture in the

base. The brake arm is operated by the small lever *k* projecting through the front of the box *A*¹ and adapted, on being pressed down, to wedge the arm *K* forward and bring the brake against the edge of the disc *b*. The device can therefore be brought to a standstill immediately.

The constructions shown in Figures 1 to 8 are of rotating disc type but the methods already described may be applied to apparatus in which the moving member is of other form and in Figure 10 a diagrammatic representation of a rotating drum device is shown. *B*² is the rotating drum or cylinder above which is placed the receiver *F* or equivalent device, such as a diaphragm, with pin *f* resting on the pad *C*³. The latter is mounted upon a flexible member in the form of a strap *D*¹ lapping around a substantial part of the cylinder and of any suitable gripping material. A cork strap with thin steel backing has been found suitable. One end of the strap is connected to the diaphragm *E* while the other may be free or attached to a spring as in the case of the flexible members shown in the other figures. The large surface of grip enables considerable magnification to be obtained without much pressure on the pad. If desired the grip may be increased by grooving the drum and making the gripping member of form corresponding to the groove so that it lies closely against the grooved surface.

What I claim and desire to secure by Letters Patent of the United States is:—

1. In phonic apparatus the combination comprising a movable body having a smooth surface, a rubbing member contactable with said surface, primary vibrating means, a single instrumentality connecting said primary vibrating means to said rubbing member, and secondary vibrating means connected to said rubbing member for magnifying said primary vibrations, as set forth.

2. In phonic apparatus the combination comprising a movable body having a smooth surface, a rubbing member contactable with said surface, primary vibrating means, a pin-like member of resilient material connected at one end to said primary vibrating means and at the other end to said rubbing member, and secondary vibrating means connected to said rubbing member for mag-

nifying said primary vibrations, as set forth.

3. In phonic apparatus the combination comprising a rotatable body having a polished surface, a rubbing member contactable with said surface, primary vibrating means, means directly connecting said primary vibrating means to said rubbing member, means for altering the angle of said connecting means with respect to said rubbing member while maintaining their angle constant with respect to said primary vibrating means, and secondary vibrating means connected to said rubbing member for magnifying said primary vibrations, as set forth.

4. In phonic apparatus, the combination comprising a movable body having a smooth surface, friction-producing material applied to said smooth surface in a thin film, a rubbing member contactable with said film, primary vibrating means, means connecting said primary vibrating means to said rubbing member for varying the pressure thereof upon said film and secondary vibrating means connected to said rubbing member for magnifying said primary vibrations, as set forth.

5. In phonic apparatus, the combination comprising a rotatable body of glass having a smooth surface, friction-producing material applied to said surface in a thin film, a rubbing member contactable with said film, primary vibrating means, means connecting said primary vibrating means to said rubbing member for varying the pressure thereof upon said film and secondary vibrating means connected to said rubbing member for magnifying said primary vibrations, as set forth.

6. In phonic apparatus the combination comprising a rotatable body of glass having a smooth surface, resin applied to said surface in a thin film, a rubbing member contactable with said film, primary vibrating means, means connecting said primary vibrating means to said rubbing member for varying the pressure thereof upon said film and secondary vibrating means connected to said rubbing member for magnifying said primary vibrations, as set forth.

SIDNEY GEORGE BROWN.
